California

Filed Sept. 29, 1961, Ser. No. 141,829
20 Claims. (Cl. 202—42)

This invention relates to the recovery of naphthalenic hydrocarbons from mixtures comprising the same, and in particular concerns a method of treating hydrocarbon mixtures boiling within the 390°—520° F. range and containing naphthalene and/or alkyl-substituted naphthalenes for the purpose of recovering said naphthalenic hydrocarbons in concentrated form.

The expanding use of naphthalene and alkylnaphthalenes for the production of dicarboxylic acids useful in manufacturing synthetic resins and fibers has created considerable interest in the recovery of these naphthalenic hydrocarbons from hydrocarbon fractions of petroleum origin. It is well known that certain fractions obtained from petroleum refining operations, e.g., catalytic cracking and reforming, contain considerable quantities of naphthalene and alkylnaphthalenes. However, such fractions also contain large quantities of other hydrocarbon types which have boiling points very close to those of the aforesaid naphthalenic hydrocarbons or which form azeotropes therewith. In either case, satisfactory separation of the naphthalenic from the non-naphthalenic hydrocarbons cannot be accomplished by fractional distillation.

Accordingly, the principal object of the present invention is the provision of an improved method for treating hydrocarbon mixtures boiling within a 390°—520° F. range and comprising naphthalene and/or alkylnaphthalenes to separate said naphthalenic materials from non-naphthalenic hydrocarbons present in the mixture. A more particular object of the invention is to provide a method whereby non-naphthalenic hydrocarbons boiling in the naphthalene range, that is, within the range of about 400°—450° F., can be readily separated from mixtures of such hydrocarbons with naphthalene. Other and related objects will become apparent to those skilled in the art as the description of the invention proceeds.

We have discovered that the above objects and attendant advantages can be realized in an azeotropic distillation process in which a glycol formate is employed as the azeotrope former. More particularly, we have found that the glycol formates form azeotropes of unusually low boiling point with non-naphthalenic hydrocarbons boiling within the 390°—520° F. range, so that by admixing a glycol formate with a mixture comprising naphthalenic and non-naphthalenic hydrocarbons boiling within said range, and subjecting the resulting mixture to distillation, an exceptionally efficient separation of the two types of hydrocarbons can be achieved. The non-naphthalenic hydrocarbons distill overhead in the form of low-boiling azeotropes with the glycol formate, leaving the naphthalenic material behind as distillation bottoms. The azeotropic distillate is rich in hydrocarbons and has a relatively low heat of vaporization, so that the amount of heat required to separate a unit volume of non-naph-

2

thalenic hydrocarbons from the feed mixture is relatively low.

We have discovered that the glycol formates exhibit a highly selective action toward the non-naphthalenic hydrocarbons when employed as azeotrope formers in the above manner and hence lower reflux ratios and fewer plates in the distillation column are required to effect the desired separations. Moreover, the glycol formates form two phases with non-naphthalenic aromatic hydrocarbons taken overhead, so that in many instances substantially complete separation of the azeotrope former from the distillate can be achieved by simple gravity settling, without the necessity of utilizing elaborate secondary equipment for that purpose. Following removal of non-naphthalenic hydrocarbons, the naphthalenes contained in the remaining bottoms fraction can be easily recovered by non-azeotropic distillation, or by any other desired means.

Considering now the process of our invention in greater detail, the feedstock entering said process may be any mixture of hydrocarbons comprising naphthalene and/or alkylnaphthalenes and at least one non-naphthalenic hydrocarbon which cannot be separated from the naphthalenic components by simple fractional distillation. The term "naphthalenic hydrocarbon" is herein employed to designate a hydrocarbon compound whose molecule contains the characteristic naphthalene grouping:

30

Conversely, the term "non-naphthalenic hydrocarbon" designates a hydrocarbon compound whose molecule does not contain said grouping. Thus, the non-naphthalenic hydrocarbons which may be present in the feedstock include aliphatic compounds such as dodecane and higher isomeric paraffins and corresponding olefins; naphthenic compounds such as cyclohexylheptene, hexylcyclohexane, dicyclohexyl, and decahydronaphthalene; benzenoid compound such as triethylbenzene, dimethylindane, ethylindene, etc.; and partially hydrogenated naphthalenic hydrocarbons such as methyltetralin, dimethyltetralin, dihydronaphthalene and methyldihydronaphthalene. The naphthalenic hydrocarbons which may be present in the feedstock include naphthalene, the methylnaphthalenes, the dimethylnaphthalenes, the ethylnaphthalenes, the isopropynaphthalenes, etc.

While the hydrocarbon feedstocks to the process of our invention can contain any or all of the above-named compounds, the process is particularly applicable for the treatment of hydrocarbon mixtures containing naphthalene and contaminated mainly with aromatic hydrocarbons such as alkylbenzenes, alkyltetralins, alkylindanes, and the like, boiling within the naphthalene range and thereabouts, e.g., from about 400° to about 450° F. It is known that naphthalene fractions containing like-boiling paraffin hydrocarbons can be purified by azeotropic distillation with various azeotroping agents. However, a more difficult problem of separation is involved in mixtures such as those just named contaminated mainly with aromatic hydrocarbons. Petroleum fractions of this nature can be derived from various hydrocarbon conversion and refining processes commonly used in the industry, such as for ex-

ample, catalytic reforming, catalytic cracking, thermal cracking and the like. In particular, catalytic reforming of naphthas produces a heavy reformate fraction boiling above about 400° F., which may contain from about 40 to about 80% naphthalene and methylnaphthalenes. The remaining hydrocarbons in this fraction are largely alkylbenzenes, tetralins, indanes, and the like. Sometimes a significant proportion of naphthenes and paraffins are present. The recovery of substantially pure naphthalene from such petroleum fractions presents a difficult problem. Simple fractional distillation is impractical because of the close proximity of boiling points of the contaminating hydrocarbons, and also the formation of complex azeotropes.

The feedstocks suitable for treatment as taught herein are not limited to those of conventional petroleum refining origin and may be from any source such as, for example, from destructive distillation or hydrogenation of coal processes or shale oil processes. Usually, however, the feedstock will be of petroleum origin. While the feedstock may be one boiling over the entire 390°-520° F. range, it will usually be one boiling over only a selected portion of such range (e.g., the 400°-450° F. fraction described above or a fraction boiling at 450°-470° F. and comprising monomethylnaphthalenes, etc.) and may of course contain some components boiling somewhat below or (less desirably) above said range. The feedstock may also be one which has been pre-treated to remove part of the naphthalenic components, e.g., it may be a dealkylated petroleum hydrocarbon reformate fraction from which at least part of the naphthalene has been previously separated by crystallization.

It will be apparent to those skilled in the art that feedstocks boiling over the entire 390°-520° F. range which contain both naphthalenic and non-naphthalenic hydrocarbons distributed throughout that range do not, when subjected to our azeotropic distillation treatment, yield a continuous azeotropic overhead. Instead the overhead will vary as the distillation proceeds, sometimes being azeotropic and sometimes naphthalenic, depending upon the composition of the liquid in the still. Accordingly, to make a practical naphthalenic-non-naphthalenic separation of such mixtures by distillation means alone, it is necessary either first to separate the mixture into appropriate fractions by straight distillation and then to distil azeotropically selected fractions, or to practice a combined azeotropic-straight distillation technique on the feedstock mixture and separate the overhead products into azeotropic and straight distillate categories. The above procedures can be practiced in numerous ways, incorporating batch, flow and hybrid batch-flow methods of operation, as will be apparent to those familiar with the distillation art.

Best results are achieved in the practice of our invention when the feed to any given azeotropic distillation step has a boiling point range spread no greater than about 50° F. It is of course desirable, in many cases, to have much narrower boiling point spreads, as exemplified by the monomethylnaphthalene fractions boiling from about 450° to about 470° F. referred to above. In any event, it is generally true that the narrower the boiling point spread of a feed fraction, the cleaner will be the split between its naphthalenic and non-naphthalenic fractions in our azeotropic distillation operation. The boiling point range from about 390° to about 520° F. is sufficiently broad to encompass the three naphthalenic hydrocarbon fractions, namely, the naphthalene fraction, the monomethylnaphthalene fraction and the dimethyl-naphthalene fraction, most often encountered in naphthalene dealkylation feedstocks.

Our invention has particular utility for the treatment of hydrocarbon fractions fitting above-indicated categories which contain naphthalene fractions comprising naphthalene and non-naphthalenic hydrocarbon material boiling within about 10° F. thereof, and especially such pe-

roleum fractions in which the naphthalene fraction boils over the entire range from about 410° to about 450° F. and one or more of the alkylbenzenes, alkyltetralins and alkylindanes comprises the non-naphthalenic hydrocarbon material. More specifically, petroleum fractions within the above class which have been found particularly amenable to treatment by the method of this invention are those boiling above about 400° F. which include, as non-naphthalenic hydrocarbons, alkylbenzenes, alkyltetralins and alkylindanes boiling over the range from about 410° to about 435° F.; heavy naphtha reformates boiling above about 400° F. and including a naphthalene fraction boiling over the range from about 410° to about 450° F. which preferably contains alkylbenzenes, alkyltetralins and alkylindanes; and heavy naphtha reformates which have been subjected to catalytic hydrodealkylation, boiling above about 400° F. and including a naphthalene fraction boiling over the range from about 410° to about 450° F., which naphthalene fraction preferably contains alkylbenzenes, alkyltetralins and alkylindanes.

Procedure-wise, our process is carried out as a conventional azeotropic distillation operation, and any of the techniques commonly applied to such types of operation are applicable to the present process. In its simplest embodiment, namely, batch distillation, the process consists essentially of adding to the feedstock sufficient glycol formate to form azeotropes with the non-naphthalenic components, and thereafter distilling the mixture in a reasonably efficient distillation column. The azeotropic distillate is condensed and passed to a separator where the condensate is allowed to separate by gravity into two phases, one of which comprises the non-naphthalenic components of the feedstock containing a small quantity of glycol formate and the other of which comprises glycol formate containing a relatively small quantity of dissolved non-naphthalenic hydrocarbons. Either or both of said phases may be redistilled or otherwise treated to recover the azeotrope former for reuse. The naphthalenic components of the feedstock are contained in the bottoms fraction which constitutes the desired end product of the process.

In practicing the process of our invention on those naphthalene-aromatic hydrocarbon feedstock mixtures for the separation of which it is most applicable, we have found that substantially all of the alkylbenzenes, alkyltetralins, and alkylindanes which boil within about 30° F. of naphthalene can be efficiently azeotroped overhead before any substantial amounts of naphthalene appear in the overhead product. Moreover, it is found that the azeotropic overhead is unexpectedly rich in hydrocarbons, containing only about 50 to about 80 percent by weight of glycol formate, thus minimizing the distillation load, and the amount of azeotroping agent required.

Attention is now directed to the accompanying drawing, which illustrates schematically one method of practicing the azeotropic distillation process of this invention. The initial feedstock is brought in through line 2 and admitted to distillation column 4 wherein the primary azeotropic distillation takes place. Column 4 may be a conventional fractional distillation column containing, for example, 20-80 plates and may be operated at overhead reflux ratios of, e.g., 1:1 to 20:1. Azeotroping is continued until essentially all of the non-naphthalenic hydrocarbons boiling within about 10° F., and preferably 20° F., of naphthalene are distilled overhead. The overhead temperatures during the azeotropic distillation will usually range between about 335° and about 360° F., the glycol formates themselves boiling within the range from about 335° to about 366° F. The azeotropic overhead is taken off through line 6 and condensed in condenser 8, and the resulting condensate is transferred by line 10 to a liquid phase separator 12. To provide the desired reflux ratio, a portion of the condensate in line 10 may be diverted through line 16 and admitted to the top of column 4.

In phase separator 12, the condensate may separate spontaneously into two phases, or a small proportion of a miscibility reducing agent may be required, depending upon the nature of the feed. If the feed is rich in lower alkylated aromatics a miscibility reducing agent is ordinarily required, but if it is rich in higher alkylated aromatics and/or in naphthalenes, adequate phase separation occurs spontaneously. Suitable miscibility reducing agents include anti-solvents for the glycol formates, e.g., paraffinic or naphthenic hydrocarbons such as pentane, decane, cyclohexane or the like. Other suitable miscibility reducing agents are the lower glycols such as ethylene glycol, propylene glycol, etc. Preferably, the miscibility reducing agent should be easily separable, as by distillation, from the phase in which it is dissolved.

The glycol formate rich phase which stratifies in separator 12 will ordinarily contain about 1 to about 25% by weight of dissolved hydrocarbons, and this solution is continuously recycled via line 14 back to a mid-point in distillation column 4.

The hydrocarbon rich phase in separator 12 ordinarily will contain about 1 to about 15 percent by weight of dissolved glycol formate. This hydrocarbon rich phase is then transferred via line 16 to fractionating column 20, from which the glycol formate is distilled overhead via line 22 as an azeotropic distillate with a portion of the non-naphthalenic hydrocarbons, and condensed into separator 12. The azeotropic distillate from column 20, as well, incidentally, as that of column 4, is a minimum boiling azeotrope in the sense that the various azeotropic combinations involved are minimum boiling azeotropes. The non-naphthalenic hydrocarbons are withdrawn as bottoms from column 20 via line 24.

A naphthalene-containing bottoms fraction is continuously withdrawn from distillation column 4 via line 26, and transferred to naphthalene fractionating column 23. Since substantially all of the close-boiling non-naphthalenic hydrocarbons have been removed in column 4, the principal separation which is achieved in column 23 is normally the separation of naphthalene from alkyl-naphthalenes such as for example, methylnaphthalenes. The naphthalene overhead is withdrawn via line 30 and condensed in cooler 32 to substantially pure naphthalene crystals melting at about 80° C. These crystals are normally in excess of 99% pure. The alkyl naphthalene bottoms from column 23 is withdrawn via line 34 and may be sent to dealkylation facilities not shown on the drawing to produce additional naphthalene. Such dealkylation facilities may be those of any conventional catalytic hydrodealkylation process. An especially preferred technique for dealkylating methylnaphthalenes employs steam and hydrogen at elevated temperatures and pressures over a cobalt-molybdate catalyst, as is more particularly described in U.S. Patent No. 2,734,929 to Doumani. Where the column 23 bottoms product is subjected to dealkylation, the resulting dealkylate can be recycled to admixture with the feed to column 4 if desired.

The foregoing is not to be considered limitative of the scope of our process. As those skilled in the art will appreciate, other conventional azeotropic techniques may be employed, and other conventional methods such as fractional crystallization may be employed to recover naphthalene from the azeotroping bottoms.

An important advantage not heretofore mentioned of the use of our glycol formates as azeotrope formers, over the use of other materials for this purpose, is the fact that the glycol formates do not form azeotropes with naphthalene. This has obvious benefit in that, for one thing, it makes for easier control in the practice of the process. We have found the glycol formates to be non-corrosive to mild steel and this of course gives them an advantage over competitive azeotrope formers, such as, e.g., certain of the organic amine salts. The beneficial aspects of such lack of corrosivity in equipment and preventive maintenance cost savings are obvious. Slight decomposition of the formates occurs on refluxing at atmos-

pheric pressure. However, this can be almost entirely eliminated by operating at reduced pressures. An additional benefit of the use of reduced pressures is that improved alphas and azeotropic overhead compositions are thereby realized.

The glycol formate azeotrope formers of this invention include glycol diformates, glycol monoformates and mixtures thereof. These esters have been found to possess unique superiority as azeotropic agents for separating naphthalene from other hydrocarbons, in which respect they are greatly and unexpectedly superior to their acid-substituted homologs, including even the glycol acetates. The glycol formates of either mono- or diformate identity as readily prepared by well known methods. A simple way to prepare them is simply to formulate the appropriate glycol, or glycols, with formic acid or formic anhydride. The glycol moieties of our azeotrope formers can be of any size and character consistent with an operative boiling point level in the azeotrope former. Preferred glycols for purposes of our invention, as determined primarily by boiling point considerations, are those having four carbon atoms or less, typical of which are: ethylene glycol; 2,3-butanediol; 1,4-butanediol; 1,2-butanediol; trimethylene glycol; diethylene glycol; and propylene glycol. As will be apparent from the foregoing list, the class of glycol formates suitable for use as azeotrope formers in our invention includes glycol ether formates such as, for example, diethylene glycol formates.

Our preferred azeotrope former, for reasons of ready availability, low cost and excellence of result, is ethylene glycol diformate. However, it is within the scope of our invention, and even preferred in many cases, to employ a mixture of ethylene glycol mono- and diformates having suitable solubility characteristics for the hydrocarbon stock being treated. For highly aromatic stocks, a higher proportion of mono-formate is normally desirable. In any event, where such a mixture of formates is employed a ternary azeotrope containing hydrocarbon, mono- and di-formate is produced. Other mixtures of individually suitable formates, such as mixtures of mono- and diformates and/or glycol formates of differing glycol entities, can likewise be used within the scope of our invention.

The effectiveness of our process is more particularly illustrated by the following examples. These examples are, however, not to be construed as limitative, but merely exemplary, in purpose.

EXAMPLE I

This example is included to illustrate the inefficacy of straight distillation as a means of separating naphthalenic from non-naphthalenic hydrocarbons in admixture therewith.

The 400°-550+° F. fraction of a reformate product was separated therefrom by distillation and subjected to a hydrocarbon type analysis. The results of the analysis are set forth below.

Components:	Percent by weight
Alkanes	7.6
Mono-naphthalenes	2.3
Poly-naphthalenes	2.1
Alkylbenzenes	22.1
Tetralin-indanes	24.8
Naphthalenes ¹	37.8

¹ The distribution of the naphthalenes was found to be as follows (the figures representing weight percentages of the total sample):

C ₁₀ H ₈	8.7
C ₁₁ H ₁₀	21.0
C ₁₂ H ₁₂	6.4
C ₁₃ H ₁₄	1.3
C ₁₄ H ₁₆	0.3
C ₁₅ H ₁₈	0.1
	37.8

The 400°-550+° F. reformate fraction was subjected to batch distillation in a 30-plate Oldershaw column at

a 10:1 reflux ratio and in the absence of an azeotroping agent. The fractions obtained from the batch distillation were analyzed for hydrocarbon types. Results of these analyses appear in Table 1 below:

Table 1

Boiling Point, ° F.	400-420	420-430	430-435	435-440	440-445	445-450	450-455	455-460	460-465	465-470	470-475	540-550
Weight percent	18.5	18.3	5.07	7.14	5.65	3.38	2.04	2.44	4.22	13.3	14.46	0.40

Poly-naphthalenes	1.9	2.2	2.7	2.6	2.8	3.1	2.9	2.8	1.0	0.7	0.5	0.5
Alkylbenzenes	34.5	34.1	34.0	34.2	32.2	28.8	20.1	16.3	10.9	4.4	2.6	3.9
Tetralin-indanes	28.9	30.8	39.0	38.9	44.1	48.5	41.7	36.4	26.8	9.1	4.8	1.5
Naphthalenes	18.5	19.2	10.9	11.0	8.8	9.1	27.1	39.7	53.3	85.1	80.6	53.2
$C_{10}H_{18}$	17.7	18.6	10.2	10.2	6.7	5.1	3.8	2.6	1.7	0.7	3.8	3.0
$C_{11}H_{10}$	0.2	0.4	0.5	0.6	1.8	3.6	23.2	36.5	56.0	83.8	27.3	1.5
$C_{12}H_{12}$											41.9	11.6
$C_{13}H_{14}$	0.2										0.5	29.2
$C_{14}H_{10}$							0.1	0.1			0.6	7.2
$C_{15}H_{18}$												0.3

In evaluating the Table 1 data, it will be noted that the bulk of all components of the feedstock except the higher boiling alkylnaphthalenes distilled off in the fractions within the boiling point range from 400° to 450° F. It will be further noted that none of the six fractions within that range show any practically significant enrichment in either naphthalene or non-naphthalenic hydrocarbons over the starting material.

Turning next to the higher boiling fractions, particularly those between 450° and 540° F., it will be observed that no "practical" selectivity was effected there either. Thus, while the bulk of the alkylnaphthalene portion of the feed distilled within that range there was also much alkylbenzene and tetralin-indane distillation therein to mitigate against economically acceptable selectivity. This was particularly true of the boiling point range from 450° to 465° F.

EXAMPLE II

This is an example of a continuous azeotropic distillation of a reformate fraction boiling between 400° and 445° F., using a mixture of ethylene glycol monoformate and ethylene glycol diformate, in a weight ratio of the former to the latter of one, as the azeotrope former. Here, and elsewhere herein, the term "azeotrope former" is loosely used to connote, or generically include, mixtures of glycol formates where such usage appropriately applies. We also employ the term, where appropriate, to refer to individual glycol formates.

The reformate fraction contains 43 weight percent naphthalene and 1 weight percent methylnaphthalene, the remainder being alkanes, naphthalenes, alkylbenzenes, tetralins and indanes. The azeotrope former is employed in a ratio of 80 volumes per 100 volumes of reformate feed. The distillation column employed is a conventional vacuum jacketed glass Oldershaw column with 60 perforated plates of 28 mm. I.D., each having 82 holes of 0.89 mm. diameter. The plate to plate spacing is approximately 27 mm. The distillation is conducted at a reflux ratio of 5:1.

In carrying out the continuous distillation of this example, the reformate feedstock is continuously introduced into the 60-plate Oldershaw column along with a properly proportioned volume of the azeotrope former. The column is operated to produce an overhead vapor stream at a temperature of about 342° F. and a bottoms fraction boiling above about 425° F. The latter fraction is continuously withdrawn from the bottom of the Oldershaw column as the process product, and comprises about 98 percent by weight naphthalene.

The overhead from the column is condensed and separated into two phases—a hydrocarbon phase comprising primarily non-naphthalenic components of the feedstock, but including about 2 percent by weight of the azeotrope former, and a glycol formate phase.

The bottoms product from the azeotropic distillation is

subjected to straight batch distillation in a 30-plate Oldershaw column at a reflux ratio of 5. The overhead product is a phthalic grade naphthalene of 79° C. melting point. The overall recovery of naphthalene is about 88 percent.

The result of this example clearly illustrate the excellent selectivity attainable through the use of glycol formates as azeotrope formers in the method of our invention. They also illustrate that such selectivity is not dependent upon the use of large quantities of azeotrope former but, on the contrary, that relatively small quantities are sufficient for the purpose. Thus, in the present example the ratio of azeotrope former to non-naphthalene feedstock hydrocarbons, on a volume basis, is only 1.4:1.

EXAMPLE III

This example demonstrates the superiority of our glycol formates as azeotrope formers over their corresponding acetate esters and also their superiority over the straight glycols.

A batch distillation was conducted on a hydrocarbon stock containing naphthalene, in the presence of ethylene glycol diformate in a ratio of 83 volumes of the diformate per 100 volumes of the stock. The hydrocarbon analysis of the stock showed that it contained 57% non-naphthalenic compounds.

Two other batch distillations were run, each similar in every respect to the above-described one except that in one case ethylene glycol diacetate (instead of ethylene glycol diformate) was employed as the azeotrope former and in the other case propylene glycol was so employed. The amount of hydrocarbon removed as an azeotropic overhead without taking naphthalene overhead was determined for each of the three runs as a measure of the selectivity of the azeotrope former tested. The results are shown below.

	Weight percent of hydrocarbon removed relatively free of $C_{10}H_{18}$
Azeotrope former:	
Propylene glycol	12
Glycol diacetate	21
Glycol diformate	37

The above results clearly illustrate the great superiority of glycol formates over the straight glycols as azeotrope formers for our purposes. They likewise illustrate that the glycol formates are greatly and unexpectedly superior to their close acetate homologs as selective azeotrope formers for use in the process of this invention.

EXAMPLE IV

This example is illustrative of the separation of non-naphthalenic hydrocarbons from alkylnaphthalenes according to the method of this invention.

A bottoms fraction of a platinum-catalyzed reformer product have a boiling range of 385-440° F. is hydrodealkylated over a cobalt oxide-molybdenum oxide catalyst to produce a dealkylated product boiling over the range 141°-550° F. This product is fractionally distilled to obtain a light gasoline fraction boiling at 141°-401°

F., a naphthalene fraction boiling at 401°-438° F., a methylnaphthalene fraction boiling at 456°-467° F., and a heavy fraction boiling at 493°-550° F. Analysis shows the methylnaphthalene fraction to contain about 90.5 percent by weight of 1- and 2-methylnaphthalenes and about 9.5 percent by weight of non-naphthalenic hydrocarbons, presumably alkyltetralins and alkylindanes. This material, together with 40 percent by weight of ethylene glycol monoformate, is introduced into a 20 plate Oldershaw column and a distillation is carried out therein to yield a bottoms product enriched in methylnaphthalenes.

EXAMPLE V

This example illustrates an azeotropic distillation according to this invention in which propylene glycol diformate is used as the azeotrope former.

A quantity of a reformate fraction containing 43 weight percent naphthalene and 1 weight percent methylnaphthalene, the remainder being alkanes, naphthenes, alkylbenzenes, tetralins and indanes, together with 30 percent by weight propylene glycol diformate is introduced into a 40 plate Oldershaw column and a distillation is carried out therein to yield a bottoms product enriched in naphthalene.

EXAMPLE VI

This example is illustrative of the separation of non-naphthalene hydrocarbons from naphthalene according to the method of this invention using a mixture of trimethylene glycol monoformate and 1,4-butanediol diformate as the azeotrope former.

A quantity of a reformate fraction containing 43 weight percent naphthalene and 1 weight percent methylnaphthalene, the remainder being alkanes, naphthenes, alkylbenzenes, tetralins and indanes, together with 20 percent by weight of a mixture of trimethylene glycol monoformate and 1,4-butanediol diformate in a molar proportion of the former to the latter of one, is introduced into a 40 plate Oldershaw column and a distillation is carried out therein to yield a bottoms product enriched in naphthalene.

It will be apparent that the method of our invention is applicable for use in the separation of many hydrocarbon mixtures other than those described in the above examples. Thus, any hydrocarbon mixture amenable to such treatment within the purview of our invention can be separated into non-naphthalenic and naphthalenic fractions by azeotropically distilling it in the presence of a suitable glycol formate azeotrope former in accordance with the teachings herein. Furthermore, the azeotropic distillation technique of this invention can be incorporated in, or combined with, existing dealkylation methods in a variety of ways to yield a corresponding variety of new processes for the treatment of hydrocarbon mixtures such as those herein identified as suitable feedstock materials. Illustrative examples of two such composite processes are described below. It is emphasized that the descriptions of these processes are included purely for illustrative purposes and that no limitative significance should be attached to the particular step sequences and flow arrangements there disclosed. Many other composite azeotropic distillation-dealkylation processes within the scope of this invention can be readily visualized.

Both of the above-mentioned processes are designed to treat, by a combination of azeotropic distillation and dealkylation techniques, hydrocarbon mixtures boiling within the range from about 390° to about 520° F. and containing naphthalene and non-naphthalenic hydrocarbons not separable therefrom by fractional distillation, as well as alkylnaphthalenes. The object of each process is, of course, to obtain by fractionation and dealkylation means as much naphthalene as possible from the feedstock mixtures.

Briefly, one of said processes comprises fractionally distilling the feedstock to obtain a first overhead of naph-

thalene and non-naphthalenic hydrocarbons boiling within the range from about 390° to about 425° F. and a first bottoms product enriched in alkylnaphthalenes boiling within the range from about 425° to about 520° F.; azeotropically distilling said first overhead using a glycol formate as the azeotrope former to thereby remove non-naphthalenic hydrocarbons overhead in the form of an azeotropic distillate and yield a naphthalene-enriched second bottoms product; subjecting the first bottoms product to a dealkylation treatment; fractionally separating the effluent from said dealkylation treatment into a light fraction containing gasoline, a heart-cut naphthalene fraction and a heavy fraction; and recycling said heavy fraction to the dealkylation treatment.

In the second illustrative process the feedstock is fractionated to remove a light gasoline fraction, boiling below about 415° F. a naphthalene fraction boiling between about 415° and about 430° F. and a heavy fraction boiling above about 430° F. which is enriched in alkylnaphthalenes. Said naphthalene fraction is subjected to azeotropic distillation in accordance with the teachings herein to yield a naphthalene bottoms product and an azeotropic overhead containing non-naphthalenic hydrocarbons boiling below about 430° F., which hydrocarbons can be removed by phase separation means and blended with the aforesaid light gasoline fraction. Said heavy fraction enriched in alkylnaphthalenes is subjected to a dealkylation treatment and the normally liquid portion of the effluent therefrom is blended with fresh feedstock to the overall process.

As will be evident from the foregoing teachings, the azeotropic distillation feature of our invention can be viewed either as an independent entity or as one element of a combination azeotropic distillation-dealkylation process of the type just described. This vantage point distinction is of importance in fixing the breadth of the class of azeotrope formers in a given embodiment. Thus, when the azeotropic distillation procedure is viewed as an independent entity, the gist of the invention is felt to reside in the use of a particular kind of azeotrope former (from the glycol formate class set forth and claimed herein) whereas, when it is integrated with a dealkylation process and viewed as one element of the resulting combination it is felt that patentability resides broadly in the combination and not in the identity of the azeotrope former. Hence, in the former case the claims are limited to glycol formate azeotrope formers whereas in the latter case they are not so limited but are broad as to suitable azeotrope formers. Examples of azeotrope formers other than glycol formates which are useful for the dealkylation embodiments of our invention are butyrolactone and N-methyl formamide. For detailed descriptions of the use of these two materials as azeotrope formers for the separation of non-naphthalenic hydrocarbons from mixtures containing naphthalene, such as those of present interest, see copending U.S. patent applications of Serial Numbers 19,526 and 82,496, filed April 4, 1960, and January 13, 1961, respectively.

We claim:

1. A process for treating a hydrocarbon mixture boiling within the range from about 390° F. to about 520° F., and comprising naphthalenic and non-naphthalenic components which are not separable by simple fractional distillation, which comprises: azeotropically distilling said mixture together with a glycol formate to vaporize said non-naphthalenic components together with said glycol formate as a minimum boiling azeotropic distillate; and recovering as azeotropic bottoms a product in which the ratio of naphthalenic to non-naphthalenic hydrocarbons is substantially greater than the ratio thereof in said hydrocarbon mixture.
2. The process of claim 1 wherein said hydrocarbon mixture boiling within the range from about 390° to about 520° F. has a boiling range spread no greater than about 50 Fahrenheit degrees.

3. A process as defined by claim 1 wherein said naphthalenic components of said hydrocarbon mixture include naphthalene.

4. The process of claim 1 wherein the glycol portion of the glycol formate has no more than four carbon atoms.

5. The process of claim 1 wherein said glycol formate is ethylene glycol diformate.

6. The process of claim 1 wherein said glycol formate is a mixture of a major proportion of ethylene glycol monoformate and a minor proportion of ethylene glycol diformate.

7. A process for treating a hydrocarbon mixture boiling within the range from about 390° F. to about 520° F., and having a boiling range spread no greater than about 50 Fahrenheit degrees, comprising naphthalenic and non-naphthalenic hydrocarbons which are not readily separable by simple fractional distillation means, comprising: (1) subjecting a mixture of said hydrocarbon mixture and a formate of a glycol having no more than four carbon atoms to a first distillation under conditions such as to separate therefrom a first azeotropic distillate, consisting essentially of non-naphthalenic hydrocarbons together with the glycol formate, and a liquid bottoms fraction enriched in naphthalenic hydrocarbons; (2) condensing said first distillate and allowing it to separate into two liquid phases, a first phase comprising glycol formate and a minor proportion of non-naphthalenic hydrocarbons and a second phase comprising non-naphthalenic hydrocarbons and a minor proportion of glycol formate; (3) returning said first phase to said first distillation; (4) subjecting said second phase to a second distillation to obtain a second azeotropic distillate of glycol formate and non-naphthalenic hydrocarbons and a bottoms product comprising non-naphthalenic hydrocarbons; and (5) combining said second azeotropic distillate with said first azeotropic distillate.

8. A process as defined by claim 7 wherein said naphthalenic fraction of said hydrocarbon mixture includes naphthalene.

9. A process as defined by claim 7 wherein said non-naphthalenic fraction of said hydrocarbon mixture includes at least one hydrocarbon type from the class consisting of alkylbenzenes, alkyltetralins and alkylindanes.

10. The process of claim 7 wherein said glycol formate is ethylene glycol diformate.

11. The process of claim 7 wherein said glycol formate is a mixture of a major proportion of ethylene glycol monoformate and a minor proportion of ethylene glycol diformate.

12. A method for the recovery of substantially pure naphthalene from a petroleum fraction comprising naphthalenic and non-naphthalenic components not readily separable by simple fractional distillation, boiling above about 400° F., which comprises: (1) subjecting said fraction to azeotropic distillation in admixture with a formate of a glycol having no more than four carbon atoms until

a major proportion of the non-naphthalenic hydrocarbons in said fraction which boil within about 10 Fahrenheit degrees of naphthalene is distilled overhead with said glycol formate as an azeotropic distillate; and (2) recovering substantially pure naphthalene from the remaining bottoms fraction of said azeotropic distillation.

13. The method of claim 12 in which said non-naphthalenic components include alkylbenzenes, alkyltetralins and alkylindanes boiling within the range from about 410° F. to about 435° F.

14. The method of claim 12 in which said petroleum fraction is a heavy naphtha reformate including a naphthalene fraction boiling over the range from about 410° F. to about 450° F.

15. The method of claim 12 in which said petroleum fraction is a heavy naphtha reformate which has been subjected to catalytic hydrodealkylation and which includes a naphthalene fraction boiling within the range from about 410° F. to about 450° F.

16. The method of claim 12 in which said glycol formate comprises ethylene glycol diformate.

17. A method for the recovery of substantially pure naphthalene from a petroleum distillate including a naphthalene fraction boiling within the range from about 410° F. to about 450° F., said naphthalene fraction also containing alkylbenzenes, alkyltetralins and alkylindanes,

25 which comprises: (1) subjecting said fraction to azeotropic distillation in admixture with a formate of a glycol having no more than four carbon atoms until substantially all of the non-naphthalenic hydrocarbons in said fraction which boil within about 20 Fahrenheit degrees of naphthalene are distilled overhead as an azeotropic distillate with the glycol formate; and (2) distilling the remaining bottoms fraction from said azeotropic distillation in the absence of glycol formate to recover substantially pure naphthalene as an overhead product.

18. The method of claim 17 in which said petroleum distillate is a heavy naphtha reformate which has been subjected to catalytic hydrodealkylation and which boils above about 400° F.

19. The method of claim 17 in which said glycol formate is a mixture of a major proportion of ethylene glycol monoformate and a minor proportion of ethylene glycol diformate.

20. The method of claim 17 in which said petroleum distillate is a heavy naphtha reformate boiling above about 400° F.
